No. 845,544.

PATENTED FEB. 26, 1907.

W. C. GORDON.

WIRING KNOB.

APPLICATION FILED NOV. 20, 1905.

UNITED STATES PATENT OFFICE.

WALDO C. GORDON, OF WINDSOR, VERMONT, ASSIGNOR TO THE ELECTRIC GOOD MANUFACTURING COMPANY, OF MAINE.

WIRING-KNOB.

No. 845,544.

Specification of Letters Patent.

Patented Feb. 26, 1907.

Application filed November 20, 1905. Serial No. 288,249.

To all whom it may concern:

Be it known that I, WALDO C. GORDON, a citizen of the United States, and a resident of Windsor, in the county of Windsor and State of Vermont, have invented a new and Improved Wiring-Knob, of which the following is a full, clear, and exact description.

My invention relates to a wiring-knob or insulator for use in gripping and supporting wires for conducting electricity.

The principal objects of the invention are to provide for more securely holding wires than has been the case with prior inventions of this character, and especially for so constructing the cap with which these insulators are usually provided that it will grip the wire equally at all times independently of the position in which it may be placed on the base of the knob so long as it is centered with respect thereto.

Further objects of the invention will appear below.

Reference is to be had to the accompanying drawings, forming a part of this specification, in which similar characters of reference indicate corresponding parts in all the figures.

Figure 1 is a sectional view on the line 1 1 of Fig. 3, showing a wiring-knob constructed 30 in accordance with the principles of my invention. Fig. 2 is a central sectional view of the same at right angles to Fig. 1. Fig. 3 is a plan of the face of the knob. Fig. 4 is a bottom plan of the cap. Fig. 5 is a view similar 35 to Fig. 1, showing additional features which can be employed; and Fig. 6 is a bottom plan of the cap shown in Fig. 5.

The wiring-knob, as has previously been the case, comprises three elements—a base *a*, 40 a cap *b*, and a screw *c* or the like for holding the base and cap together. I have shown my invention as applied to that type of knobs in which the bolt is centrally located with respect to the knob and affords means for 45 quickly centering the other two parts with respect to each other. Knobs have usually been constructed with one or more straight grooves through them, both in the body of the knob and in the cap. In order to employ these knobs, it is always necessary to 50 turn the cap on the base until the grooves in the cap and base coincide with each other. I have provided means for overcoming this difficulty. In the base I provide one or

more grooves *a'*, these grooves being provided with corrugations *a²*.

In the form shown in Fig. 5 I have shown a projection or hump *a³* in the groove *a'* for the purpose of forcing the wire upwardly at the center to engage the under surface of the 60 cap *b*. The cap is flat and is provided with a circular depression *b'* for receiving a projection *a⁴* at the center of the base. Around this depression is an annular groove *b²*, the under side of which is preferably provided 65 with radial corrugations *b³*. On the outside of the groove *b²* is a surface *b⁴*, which is flat, except for a series of circular corrugations *b⁵*. In this it will be readily seen that the cap does not have to be turned to any particular 70 position in order to provide for effectively gripping a wire. As shown in Fig. 1, the wire rests on the corrugated groove *a'* and is secured by the corrugations *b³* at the sides of the lower surface of the cap; but especially 75 when the projection *a³* is employed the wire will be forced upwardly to the surface *b⁴*, and the corrugations *b³* will then assist in holding the wire. By placing two sets of corrugations on the cap, making an angle with each 80 other, it will be seen that under all conditions the wire is securely held in position.

Having thus described my invention, I claim as new and desire to secure by Letters Patent—

1. A wiring-knob or insulator comprising a base having at one side of its center a groove for a wire and a cap having a circular surface for engaging the wire, the said surface for engaging the wire lying within the circle 90 of the base whereby said surface will operate upon that portion of the length of the wire lying in the groove of said base.

2. A wiring-knob or insulator comprising a base having a straight groove for a wire and a cap having a circular grooved surface for engaging the wire, said surface crossing the straight groove at two points.

3. A wiring-knob or insulator comprising a base having a corrugated groove across its 100 upper surface and a cap having a flat surface crossing the groove at two points, said flat surface being provided with circular corrugations.

4. A wiring-knob or insulator comprising a base having a straight corrugated groove and a cap having a circular surface provided with 105 a series of circular grooves adapted to rest on

the upper surface of the base, said cap also being provided with a circular groove having radial corrugations and located within said circular surface.

5. A wiring-knob or insulator comprising a base having a groove for a wire and a cap having a circular surface for engaging the wire, the said surface for engaging the wire lying within the circle of the base whereby said surface will operate upon that portion of the length of the wire lying in the groove of

the said base said groove in the base being provided with a projection or hump extending toward the adjacent surface of the cap.

In testimony whereof I have signed my name to this specification in the presence of two subscribing witnesses.

WALDO C. GORDON.
